UNITED STATES PATENT OFFICE.

CLARENCE A. ANDERSON, OF CHICAGO, ILLINOIS.

CALLING MECHANISM FOR PARTY-LINE EXCHANGES.

1,248,782.

Specification of Letters Patent.

Patented Dec. 4, 1917.

Application filed March 20, 1911, Serial No. 615,470. Renewed April 21, 1917. Serial No. 163,707.

To all whom it may concern:

Be it known that I, CLARENCE A. ANDERSON, a citizen of the United States of America, and a resident of Chicago, county of Cook, and State of Illinois, have invented certain new and useful Improvements in Calling Mechanisms for Party-Line Exchanges, of which the following is a specification.

10 My invention relates to calling mechanism for party line exchanges and has for its object improvements in such mechanism for the purpose of facilitating the operations by and under the control of the central office operator.

In the accompanying drawings

Figure 1 is an elevation of the impulse sending apparatus;

Fig. 2 is a plan of the same;

20 Figs. 3, 4 and 5 are enlarged sectional elevations on line 3-3, 4-4 and 5-5, respectively, of Fig. 2;

Fig. 6 is an enlarged elevation of the switching relay and contact springs;

25 Fig. 7 is a plan of the key board by means of which the operator determines what stations shall be telephonically connected to the party line;

Fig. 8 is a side elevation of Fig. 7;

30 Fig. 9 is an elevation of the right end of Fig. 8;

Fig. 10 is a sectional elevation corresponding to Fig. 9;

35 Fig. 11 is a section on lines 11-11 of Fig. 8;

Fig. 12 is a diagram of the circuits involved; and

40 Fig. 13 is a detail of the magnet and devices used for controlling the supervisory lamp.

The impulse sending apparatus is mounted upon a bed plate shown broken away in Fig. 2. A motor M (Fig. 12) is used to drive the apparatus as will be hereinafter described. The motor shaft M¹ (Figs. 2 and 3) has a worm M² on its end which engages and turns a gear M³ on the shaft M⁴. On the other end of the shaft M⁴ is a sleeve which is moved longitudinally on the shaft by a clutch magnet A. This sleeve has a disk which is adjacent to another disk on a shaft supported in a bearing M⁶. The two disks when in engagement with each other by the action of the magnet A form a friction clutch M⁵, and the engagement of the clutch causes a driving of the pinion M⁷ on

the other end of the shaft supported in bearing M⁶. Through gearing, as shown in Fig. 4, the driving of the pinion M⁷ serves to drive the gear N in the direction shown by the arrow.

The gear N is loosely mounted on shaft N¹, and is provided with a pawl N² adapted to engage and drive a ratchet wheel N³ fast to said shaft N¹. A clock spring N⁴ (Fig. 65 2) normally holds the ratchet wheel N³ with a pin N⁵ against a stop N⁶. The construction of the parts so far described is such that when the clutch magnet A is energized the clutch M⁵ will be thrown into operation 70 and the motor M, operating through the parts described, will drive the shaft N¹, and consequently anything secured thereto, in the direction shown by the arrow of Fig. 4. When the clutch M⁵ is released by the de-energization of the magnet A, the spring N⁴ will return the shaft N¹, and parts carried thereby, to normal position with pin N⁵ against stop N⁶.

Secured to the shaft N¹ is a wheel P having notches P¹ adapted, when the wheel P is moved, to engage a pin P² mounted on a contact spring 36. Secured on the wheel P is a pin P⁶ (shown in section in Fig. 5) which normally rests between an arm P³, 85 loosely supported on the shaft N¹, and a projection on arm P⁴ pivoted on the adjacent frame. In the normal position of the wheel P, the pin P⁶ holds the arm P³ in an elevated position so that a pin P⁵ acts to 90 shift contact springs as shown in Fig. 5. When the wheel P is advanced by reason of operation of the clutch M⁵, the pin P⁶ forces the arm P⁴ downward, and as the outer end of the arm P⁴ is over the pin P⁵, the said pin P⁵ is moved so as to permit the adjacent contact springs to assume an alternate position, which alternate position is that due to their initial tension.

Pivotedly supported on the wheel P are 100 contact makers R and S which are adapted to engage insulated contact pins R¹ and S¹, respectively, supported in quadrants on suitable brackets as shown in Figs. 1, 3 and 5. These parts are so arranged that the contact makers R and S will engage their respective contact pins R¹ and S¹ alternately when the wheel P is advanced as the result of closing the clutch M⁵. The particular operations involved will become more apparent by a consideration of the circuits hereinafter to be described.

Supported at any convenient place, as on the stop N⁶ (Fig. 4), are insulated contact springs 20 and 21, one of which is provided with a piece of insulation adapted to be engaged by the pin N⁵ to open the connection between said springs in case the pin N⁵ and the parts connected thereto should move so far. These springs are in a circuit which controls the circuit through the motor, and are emergency springs for stopping the motor in case the contact makers R and S are moved farther than it is intended they shall be moved.

The key board consists of a frame, a series of keys, a magnet, and contact springs controlling the magnet. The frame consists of a top plate T, to which is secured a web T¹ terminating in a chamber T², in which chamber there is a magnet B which extends nearly the entire length of the frame. Arranged to slide and be guided in the top T and the expanded part of T¹ which forms the chamber T², are a series of keys V provided with cones V¹ on their stems, and heads V² in the chamber T² and directly over the magnet B. These keys are normally supported in an elevated position by springs V³ as shown in Fig. 10. Pivoted to the frame are bails B¹ and B² which surround the magnet B and are in the paths of the heads V² of the keys V so that when one of those keys is depressed the head V² thereon strikes a bail, B¹ or B², and turns it on its pivot. In so moving a bail, the depressed head V² comes close to the pole of the magnet B so that if a current is flowing through the magnet B at the time, the said magnet will act upon the depressed head V² as upon an armature to hold the key in its depressed position. In their normally elevated position, however, the heads V² are so far above the magnet B that said magnet does not have power sufficient to attract them against the force of their elevating springs V³.

On the bails B¹ and B² are arms B³ and B⁴ (Figs. 9 and 11) with pieces of insulation at their upper ends adapted to engage and close adjacent contact springs when one of the bails is depressed. These contact springs control a circuit through the magnet B, and the springs on one side are mere duplicates of those on the other. The consequence is that when one of the keys V is depressed a bail (B¹ or B²) is also depressed and a circuit is closed for the magnet B, and said magnet, acting upon its temporary armature V², holds its own circuit closed until it is broken by other means as will be hereinafter set forth.

Adjacent to each key V is a series of contact springs which make one series of connections when in one position and different connections when they are shifted. The mechanical operation of shifting these springs is through the cone V¹ on the stem of the

key V, and will be clearly apparent from an inspection of Figs. 9 and 10 without special description. The circuits involved in the shifting of these springs will be set forth hereinafter.

Adjacent to each key V is a number or other indicating mark, representing the station on a party line which has a similar number. Thus, the key V having "1" beside it is used in calling station No. 1, the key having "5" is used in calling station No. 5, and so on. One of the keys marked "R" in Fig. 7, is a release key and not used for any station. Another key without a mark is functionless, as far as the present application is concerned, but is provided as part of the general equipment to be properly connected and used when one key-board is provided for two operators' positions and is to be used by both operators.

There are provided an operator's telephone set, cord circuits, plugs, jacks, ringing and listening keys, and other devices ordinarily used in a central office. Of these there are shown in the diagram one jack from which a party line extends, a plug and part of one cord circuit, and a ringing key K shown in dotted lines. There are also shown an ordinary drop below the jack and a visual signal above. There is one of each of these for each party line. Connected with the party line there is shown one local station with the circuits shown with a comparative degree of fullness for the purpose of illustrating the type of local station with which the calling mechanism is usually associated and to which it is well adapted. As the present invention relates to the central office apparatus and not to that of the local stations, and as the type of local station will be recognized by those skilled in the art, the local circuits will not be given in detail.

The visual signal apparatus, however, forms an important part of the central office apparatus and will be described in enough detail to illustrate its action. It consists of a polarized magnet L¹ and armature of the same kind as those used for stepping magnets at the local stations, and this magnet is connected to the line in the same way that the stepping magnets are connected so that all impulses which affect those magnets will affect this one in the same way. The armature of the magnet L¹ is normally held in mid-position by two springs, one of which is a contact spring in the circuit for the lamp L². Pivoted in front of the armature of L¹ is a weighted lever or arm L³ which tends to remain in the position to which it is thrown by the magnet. Fig. 13 shows L³ in the position which it occupies when a stepping impulse has last been sent over the line. In this position L³ is in engagement with a contact L⁴, which in turn

is electrically connected with L^5 . When another stepping impulse flows through L^1 the pin on the lower end of the armature lever does not disturb L^3 , but the armature lever 5 pushes the spring L^5 away from the support of the contact L^4 with the result that the circuit for the lamp L^2 is broken as long as the impulse lasts. Upon the cessation of the impulse through the magnet L^1 the 10 spring L^5 again engages the support for the contact L^4 and the lamp circuit is again established. When an impulse through L^1 is of the kind used for releasing the switches, at the local stations, the weighted arm is 15 thrown to its alternate position with the result that the electrical connection between L^3 and L^4 is broken and not reestablished until another stepping impulse is sent through the magnet L^1 . As the circuit for the lamp includes the connection between L^3 and L^4 , the lamp is extinguished by this 20 action.

The operation will be explained by assuming that a subscriber at one of the stations 25 on a party line has sent in a signal to operate the drop for that line, and that the operator has inserted the plug in the jack, has answered in the ordinary way, and has learned that the calling subscriber is at station No. 1 and wishes to talk to the subscriber at station No. 12 on the same line. The operator being thus informed of what 30 stations are to be connected to each other in a talking circuit she presses keys V marked "1" and "12." It is to be noted in this connection that the contact springs associated 35 with these keys are shown at the left of the diagram, but that this diagram shows only springs for part of these keys, it being 40 understood that the springs for the additional keys are to be connected in series in the same way as those shown. In other words, the diagram shows connections complete for eight stations on one party line, 45 while Figs. 7 and 8 show a device capable of use on party lines having eighteen stations. When the operator depressed keys "1" and "12" the circuit was made for magnet B upon depression of the first one with the 50 result that both were held in depressed condition by said magnet. The circuit for the magnet B also includes the switching relay C in series with B and is as follows:—battery W —15—16— B —17—18—19—20—21— 55 22—23—24—25— C —26— W . This circuit is completed instantly upon pressing one of the station keys V , and the consequent energization of the switching relay C cuts off the generator G at the contact 75 so that 60 when the operator immediately after pressing the station keys pushes the ringing key K to the right, it is the calling mechanism and not the generator which is connected to the line.

65 Pressing the key K closes a circuit as

follows:—main battery X —27—28—29—ground at central to ground at all of the local stations on the line and then in multiple through the stepping magnets L to the tip side of the line (also signal magnet L^1 at central)—30—31—32—33—34—35—36—37—38—39—40—41— D —42— X .

The magnet D is called the starting relay and is preferably sensitive. The impulse flowing over the circuit just described is in 75 the release direction for the stepping magnets L at the local stations and consequently serves to bring the apparatus at the stations to normal position in case they were off normal when this impulse was sent. Energizing 80 the starting relay D closes a circuit as follows:—battery Y —43—44—45—46—47— A —48— Y . This not only throws the clutch M^5 but closes a circuit for the motor as follows:— Y —43—44— M —49—50—51—48— Y . 85 Also a parallel branch for itself as follows:— Y —43—44—52—53—54—55—56— A —48— Y .

The closing of the clutch M^5 and the starting of the motor M starts the wheel P 90 into motion to cause the serrations to pass over the pin P^2 to vibrate the contact spring 36, remove the pin P^5 from the adjacent reversing springs, and to move the contact makers R and S over their contact pins R^1 95 and S^1 . The first notch P^1 reached the pin P^2 at the same time that the pin P^5 permits the reversing springs to change position. The shifting of the reversing springs breaks the circuit through the starting relay 100 D and also through the stepping magnets L at the local stations. As the clutch magnet A closed a circuit for itself, the shifting of the reversing springs did not affect that 105 magnet.

The movement of the serrations P^1 over the pin P^2 vibrates the spring 36 between contact points above and below. When 36 strikes the contact below a current flows as follows:—battery X —27—57—39—38—37— 110 36—35—34—33—32—31—30—tip side of the line to all stations thereon—magnets L —ground—29—58—59— X . It will be seen that this starts from the same side of the battery as before but that it goes over the 115 line and through the stepping magnets L in the opposite direction from that previously given. This impulse is a stepping impulse and advances the ratchet wheels of all stations one step. It also operates the magnet 120 L^1 at the central office to close a circuit for the lamp L^2 and thus to indicate to the operator that the stepping impulses have begun.

When the spring 36 rises this circuit is 125 broken and another circuit over the same course is completed to the small battery Z . This battery has its poles so related to the contact spring 36 that the impulse from said battery is in a direction opposite to the step- 130

ping impulses. This impulse, however, does not release the switches at the local stations for the reason that the battery is made too small and weak to effect this result. The object of this light impulse in the reverse or release direction is to kill the residual magnetism in the magnets L and thus prevent their armatures from sticking. As the wheel P advances these stepping impulses continue to advance the ratchet wheels at the local stations. Also, each stepping impulse temporarily breaks the circuit for the signal lamp L² exhibits a series of successive flashes which indicate to the operator that the stepping impulses are going over the line. If she chooses to count these flashes she can do so and thus know how many stepping impulses are being sent. If for any reason these flashes do not appear she can know that something is wrong and have steps taken to remedy the defect. The flashes of light from the lamp L², therefore, indicate that the apparatus is working properly.

While the contact spring 36 is vibrating as described the contact makers R and S are traveling over their respective contact pins. When the contact maker R strikes a pin R¹ connected to a spring contact closed by a depressed key V, a current flows from the ringing machine or generator G as follows:—G—60—spring 61 of the highest numbered key in the row of keys in which the depressed key is located, and then on through other springs 61 until the one is reached which was moved by the depressed key V—62—63—touched contact pin R¹—R—64—65—66—67—sleeve side of the line to the local station which corresponds to the key V which was depressed—68 which is connected to the sleeve side of the line at each stepping movement of the magnet L—cut-in coil Q—ground—G.

Immediately after the last mentioned impulse is sent the contact maker S engages the pin S¹ which corresponds to the key depressed. If only one key had been depressed then a current would flow as follows:—W—15—68—69—70—and on through other contacts 69 and 70 until the contact 69 is reached which has been moved by the depressed key V—71—72—touched S¹—S—64—E—73—26—W.

The original assumption, however, was that keys "1" and "12" had been depressed for stations No. 1 and No. 12. Under these conditions this circuit will not be completed for key "1" because the contacts 69 and 70 for key "12" are not in engagement with each other, but will be completed when S strikes the pin S¹ connected to the contact 71 for depressed key "12". In the meantime, however, stepping impulses go on until contact R engages the pin R¹ connected to spring associated with depressed key "12" when the cut-in coil Q of station No. 12 will be oper-

ated the same as previously described for station No. 1. Then will follow the circuit last described passing through the spring 71 which belongs to depressed key "12". The circuit described through the release relay E causes that relay to break the connections between 23 and 24. As these contacts are in the before mentioned circuit for the magnets B and C, the break at 23—24 breaks the circuit for these magnets. Breaking the circuit for B permits the depressed keys V and their associated springs to return to normal position. Breaking the circuit for C permits the associated springs to return to their normal position which is that shown in the diagram. This last action cuts off the calling device and throws the ringing machine on the line as follows:—G—75—76—67—sleeve side of the line to stations No. 1 and No. 12—77—receiver hook-ringer-contacts closed by Q—tip side of line—30—31—32—33—78—79—80—81—82—G. This signals selected stations.

Breaking the circuit through C also breaks the circuit for the clutch magnet A at 52—53, and the release of the clutch magnet in turn breaks the circuit for the motor M at 50—51. As a consequence the advance of the wheel P is stopped the instant the contact maker S strikes the pin S¹ which corresponds to the highest numbered key V which had been depressed. The point to which it is desired to here call attention is that by building up the connections between the springs controlled by the keys V, the impulse sending device is automatically stopped the instant it has sent impulses enough to reach the highest numbered key depressed irrespective of what that number may be. Heretofore it has been the practice to send out over the line as many impulses as there were stations on the most heavily loaded party line served by the impulse sender. Thus, if a line should have twenty stations on it and station No. 1 should be the only station wanted, still twenty stepping impulses would be sent. In the present arrangement, if station No. 1 is the only one wanted, then immediately upon completion of one stepping impulse and one cut-in impulse, the apparatus will stop and return to normal position.

It has been hereinbefore stated that the operator holds the ringing key pressed to the right during the impulse sending, and that she can observe the impulse sending by the flashing of the light L². When the impulse sending device is cut off and the ringing machine G thrown on the line by breaking the circuit through the switching relay C, the flashing of the light L² ceases and the operator knows that all required stepping impulses have been sent and that the ringers of the selected stations are connected to the line. To insure the proper ringing she

holds the key K for a few seconds after the flashing of the light L² ceases, then releases it. The calling apparatus may then be used on some other party line.

5. When the subscribers have finished talking the operator is notified through an ordinary clearing out drop connected in the cord circuit, which drop is not shown as it may be of the ordinary kind and has no direct bearing upon the present invention. When the operator is so signaled she presses the key V which is marked "R" and also again presses the key K. A circuit is then completed as follows:—X—27—28—29—10 ground—all local stations on the line—L—tip side of the line—30—31—32—33—78—79—80—83—84—X. The impulse which flows from the battery X over this course is in the release direction and restores the apparatus of the local stations to normal position. A branch also goes through the magnet L¹ and extinguishes the light L². The particular key V which is marked "R" to represent "release", does not close a circuit 20 for the magnet B as it opens that circuit at 17—18, and consequently it is not automatically held down when depressed. The key "R" is also used to restore the central office apparatus to normal position before 25 stepping impulses are sent over the line in case the operator discovers that she has inadvertently pressed keys V for wrong numbers. This last is by reason of the fact that it opens the circuit for the magnet B at 30 17—18.

What I claim is:

1. The combination with a party line, of an impulse sending device, keys for indicating different stations on the party line, 40 means for connecting the impulse sending device to the line and starting the same into operation so that impulses therefrom will flow over the line, and automatically operating means for stopping the impulse sending device as soon as the impulses sent over the line are sufficient in number to telephonically connect to the line the station previously indicated by a depressed key.
2. The combination with an impulse sending device, keys for indicating different numbers of impulses to be sent, and means for holding two or more keys representing different numbers simultaneously in a depressed position, of means for starting the 55 impulse sending device into operation, means by which devices associated with the depressed key having the highest number will automatically operate to stop the sending of impulses, and means by which devices associated with all other keys will be ineffective to stop the sending of impulses.
3. The combination with an impulse sending device, and keys for indicating different numbers of impulses, a plurality of 60 which may be simultaneously in a depressed or manipulated position, of means for starting the impulse sending device into operation, and means for automatically stopping the sending of impulses when the number sent corresponds to the highest number indicated by the different manipulated keys.
4. The combination with an impulse sending device, and means for operating it, of a series of keys each of which indicates a different number of impulses desired from said device, means by which a plurality of said keys may be simultaneously in indicating position, and means by which said device is automatically stopped when the number of impulses supplied corresponds to the number called for by the highest numbered key that is at the time in its indicating position.
5. In a calling apparatus, a series of keys for indicating different stations on a party line, a magnet for holding moved keys in their moved position, means by which a circuit is completed for said magnet upon the movement of any one of said keys, an impulse sending device having its impulse sending operations controlled by a moved key, and means by which the stopping of said device breaks the circuit for said magnet.
6. In a calling apparatus, a series of keys, contact springs for each key operated by the manipulation of their respective keys, connections from the springs of different keys to a corresponding series of terminals, a contact maker adapted to be moved over said terminals, a motor for so moving it, and automatically operating means for stopping said motor when said contact maker engages a terminal corresponding to the operated springs of a manipulated key.
7. In a calling apparatus, a series of keys, contact springs for each key, a corresponding series of contact pins, connections from the different springs to corresponding pins, a contact maker adapted to be moved over said pins, a motor for so moving it, and means for automatically stopping said motor when said contact maker engages a pin connected to a spring moved by a key.
8. In a calling apparatus, a series of numbered keys a plurality of which may simultaneously be in a moved position, a corresponding series of contact springs operated by the movement of their respective keys, a corresponding series of contact points each of which is connected to a particular one of said springs, a contact maker adapted to engage the points in succession, a motor for moving said contact maker so as to cause such engagement, and means for automatically stopping said motor when said contact maker engages the point corresponding to the highest numbered key in a moved position.
9. The combination with a party line having a series of stations thereon each one of

which is provided with a stepping magnet and a cut-in magnet, of a device adapted to send enough impulses over the line to cause the operation of any one or all of the cut-in magnets, a series of keys numbered to represent the different stations on the line, means by which one or more keys moved from normal position serve to indicate desired stations and to control the impulses flowing over the line so as to cause the operation of the desired ones of the cut-in magnets, and automatically operating means for cutting off impulses from the line as soon as enough are sent to operate the cut-in magnets of indicated stations.

10. The combination with a party line and a device for sending impulses thereover, of a series of numbered keys, the numbers of which represent a definite number of impulses it is desired shall be sent over the line, and means associated with said device and manipulated keys for automatically stopping impulses over the line when the number sent corresponds to the number called for by such manipulated keys.

11. A series of numbered keys for indicating different stations on a party line, of a magnet for holding moved keys in their moved position, means by which a circuit is completed for said magnet upon the movement of any one of said keys from its normal position, an impulse sending device controlled by said keys and means by which the circuit for said magnet is broken when the impulses sent by said device are of the number required to select the station represented by the highest numbered key which is at the time in its moved position.

12. A series of numbered keys representing correspondingly numbered stations on a party line, a party line and a device for sending impulses over such line, means by which the impulses sent are controlled by the keys moved from normal position, and means by which the return of moved keys is controlled by the impulse sending device.

13. The combination with a party line, an impulse sending device, and means for connecting said device to and separating it from said party line, of automatically operating means for separating said device and line at any predetermined point in the normal operation of said device.

14. The combination with an impulse sending device, and a motor for operating it, of a relay for starting the device into operation, a circuit for said relay, a party line circuit, and means controlled by the movement of said device for breaking the circuit of the relay and for connecting the party line circuit to the device.

15. The combination with an impulse sending device, and a relay for starting it into operation, of a party line over which a circuit is completed for said relay, and

means controlled by the operation of said device for disconnecting said relay from and connecting the device to the party line.

16. The combination with a party line, an impulse sending device, a relay for starting it into operation, and a generator for sending signaling impulses over the line, of a series of keys for indicating different stations on the line, devices for holding moved keys in moved position, means by which the generator is cut off from the line upon moving any one of said keys from its normal position, means for completing a circuit for said relay over the party line, means controlled by the operation of said device for shifting the party line connection from the relay to the device and for releasing the moved key as soon as the desired number of impulses have been sent over the line, and means controlled by the release of the key for again connecting the generator to the line.

17. The combination with a party line, a series of keys for indicating stations on the line, devices for holding moved keys in moved position, an impulse sending device, and a relay for starting the device into operation, of means for operating said relay over the line, means controlled by the operation of the device for shifting the line connection from the relay to the device and for releasing previously moved keys, and means controlled by the release of the keys for again disconnecting the device from the line.

18. The combination with a party line, and an impulse sending device, of a series of keys for indicating different stations on the line and for controlling the number of impulses sent over the line by said device, devices for holding moved keys in moved position, and a special key "R" for restoring previously moved keys to normal position.

19. The combination with a party line, switching mechanism at each station thereon, and a device for sending impulses for operating such mechanisms, of a series of selecting keys for controlling said device so as to produce desired movements of the mechanisms, devices for holding moved keys in moved position, a special key "R" for restoring the moved mechanisms to normal position, and means by which said special key may also be used to restore inadvertently moved selecting keys to normal position.

20. The combination with a party line, of a series of keys indicating different stations on the party line, a signaling circuit, an impulse sending device and a circuit therefor, means whereby the depression of one of said keys disconnects the signaling circuit from the party line and substitutes the impulse sending circuit therefor, and means by which the last named circuit is disconnected when the impulse sending device has reached

a predetermined point indicated by a depressed key.

21. The combination with an impulse sending device, a series of numbered keys, a party line, and a relay for connecting the impulse sending device to the party line, of means whereby the operation of a key controls the relay to make such connection, and means by which such connection is maintained until the impulse sending device has reached a position indicated by the moved key.

22. The combination with a party line, a magnet at each local station on the line for advancing and releasing mechanism thereat,

and apparatus for sending appropriate impulses over said line and through the magnets at the stations, of a supervisory light for the party line, and a magnet for controlling said light, said last named magnet 20 being operated by the impulses sent by said apparatus and in consonance with the magnets at the local stations.

Signed at Chicago, Ill., this 18th day of March, 1911.

CLARENCE A. ANDERSON.
